UNITED STATES PATENT OFFICE.

THOMAS SHURMER, OF STOCKPORT, ENGLAND.

FEED ROLLER FOR SAWING, PLANING, AND LIKE MACHINES.

Application filed May 26, 1925, Serial No. 33,067, and in Great Britain January 1, 1925.

This invention relates to feed rollers for sawing, planing and like machines.

Hitherto feed rollers have been formed of cast iron on the circumference of which 5 teeth have been formed by milling; the face of the teeth being substantially radial and the back of the teeth being inclined to form part of a chord. Such feed rollers involve considerable work in manufacture and the 10 teeth are not generally deep enough and soon become clogged. Also, being made of cast iron they soon lose their sharpness and require to be re-cut and after a few times become too small for further use.

15 The object of this invention is to provide an improved feed roller which will overcome these disadvantages.

According to the invention the roller comprises a core in which are mounted detachable blades, means being provided to secure the blades within the core.

The accompanying drawing illustrates one form of the invention, in which:—

Fig. 1 is an elevation, a part of one of the 25 end plates being removed to show the teeth in their grooves.

Fig. 2 is an elevation.

Fig. 3 is a sectional plan, showing the 30 method of assembly of the parts.

Fig. 4 is a perspective detail view of one of the teeth.

In the form shown, representing a 5 inch feed roller, the core *a* is provided with the usual hole *b* for fitting on to the driving 35 spindle. The core is formed with 16 longitudinal grooves *c* in which are arranged blades *d* constituting the teeth of the roller, the greater part of the ends of the blades 40 lying nearly flush with the ends of the core but just longer than the core so as to be engaged and gripped by end plates *e* and *f*. The inner portions *g* of the ends of each 45 blade are however inclined so as to stand up above the ends of the core. The end plates *e* and *f* are formed with bevelled annular grooves *h*, and are secured by screws *j* to the core, the deeper portion of the 50 groove *h* being nearest to the centre. The blades *d* are thus secured from radial displacement by their inclined ends *g* lying in the grooves *h* in the end plates *e* and *f*.

In use, one end plate *e* is first secured to the core, a set of blades *d* are then inserted in the slots (see Fig. 3) and the other end

plate *f* placed in position and screwed down 55 tightly to the core. When the blades are worn they may be easily removed by taking off or easing off one end plate and new blades substituted; the worn teeth may then be resharpened when convenient.

60 The operative edges of the blades will preferably be bevelled at *k* to increase the grip in the driving direction and owing to the distance of that edge from the core, there is practically no possibility of the teeth becoming clogged. The blades may be made of any suitable steel that may be hardened, to reduce the rate of wear in use.

65 The blades may be formed with notches and the end plates formed with a corresponding annular ridge to engage them or other suitable means may be provided retaining the blade in the core and the operating edge of the blade may be made any 70 suitable shape without departing from the 75 nature of this invention.

What I claim is:—

A feed roller for sawing, planing and like machines comprising a cylindrical core having a central shaft receiving bore and provided at each end with a central boss, said core being provided in its outer portion with 80 annular series of longitudinal slots extending to the periphery of the core, said core having a relatively large solid portion between the walls of the slots and the shaft receiving bore, detachable plates of approximately oblong form and mounted in the said 85 slots and having the major portion of their side edges in flush relation with the end faces of the bore, said plates being provided at the inner portions of their ends with projecting wedge-shaped corner formations, the outer portions of the plates projecting from the core and constituting feeding teeth, an 90 annular detachable end plates fitted on the said bosses and of uniform diameter with the core and provided at their inner faces with annular grooves conforming to the configuration of and receiving the wedge-shaped 95 formations of the plates, and fastening means piercing the annular plates and securing the latter to the core at a point between the slots and the bosses.

100 In testimony whereof I have signed my name to this specification.

THOMAS SHURMER.
